US0D1072408S

(12) **United States Design Patent** (10) **Patent No.:** **US D1,072,408 S**
(45) **Date of Patent:** **** Apr. 22, 2025**

(54) **MOP**

(71) Applicant: **Taizhou Jintang Technology Co., Ltd.**
Taizhou (CN)

(72) Inventors: **Enkang Cai**, Taizhou (CN); **Yanping Zhu**, Taizhou (CN)

(73) Assignee: **Taizhou Jintang Technology Co., Ltd.**
Taizhou (CN)

(**) Term: **15 Years**

(21) Appl. No.: **29/891,308**

(22) Filed: **May 4, 2023**

(30) **Foreign Application Priority Data**

Nov. 18, 2022 (CN) 202230769032.3

(51) **LOC (15) Cl.** **07-05**

(52) **U.S. Cl.**
USPC **D32/50**

(58) **Field of Classification Search**

USPC D32/40-43, 50-52

CPC A47L 13/24; A47L 13/256; A47L 13/16

(57) **CLAIM**

The ornamental design for a mop, as shown and described.

DESCRIPTION

FIG. 1 is a first perspective view of a mop showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the mop thereof;

FIG. 10 is an exploded view of the mop thereof; and,

FIG. 11 is an enlarged view of the selected portion 11 in FIG. 2.

The even-dashed broken lines depict portions of the mop that form no part of the claimed design. The dot-dash broken lines depict enlargement indications and form no part of the claimed design.

1 Claim, 11 Drawing Sheets
